UNITED STATES PATENT OFFICE.

A. BUTTLES SMITH, OF BROOKLYN, NEW YORK, ASSIGNOR TO WILLIAM B. RANKINE AND BENJAMIN W. FRANKLIN, BOTH OF SAME PLACE.

PRINTING-TELEGRAPH.

SPECIFICATION forming part of Letters Patent No. 316,494, dated April 28, 1885.

Application filed April 23, 1884. (No model.)

To all whom it may concern:

Be it known that I, A. BUTTLES SMITH, a citizen of the United States, and a resident of Brooklyn, in the county of Kings and State of New York, have invented certain new and useful Improvements in Step-by-Step or Gold-and-Stock Recording Instruments, of which the following is a specification.

My invention relates to the class of instruments known as "printing-telegraphs," also called "step-by-step" or "gold-and-stock" recording instruments, by which a record is made on a strip or fillet of paper.

In the drawings the same letters indicate the same parts in all the figures.

Figure 1 is a plan view, looking down upon the instrument from above. Fig. 2 is a side view of the instrument, the point marked x' in Fig. 1 being presented forwardly. Fig. 3 is a vertical sectional view on the line $x x'$ of Fig. 1.

A is the base of the machine. It may be made of any suitable material, and upon it the several devices are mounted.

B is an electro-magnet, which, on the passage of the current, attracts the armature B' and its lever B'', which is pivoted at B'''.

C is the retractile spring for the armature B', which for the sake of simplicity is preferably a plate-spring. The lower end of it is attached to the base A, preferably by a regulating-screw, C', by means of which the tension of the spring on the armature B' may be regulated. The armature-lever B'' carries an anchor, D, at its forward end, which engages with the escapement E, which is fastened upon a hub, E', which turns on a spindle, E'', supported by the bracket E''', which is fastened to the base A.

The relation of the anchor D and the teeth on the escapement-wheel E is such that contact between either end of the anchor and the teeth of the escapement-wheel effects forward revolution of the type-wheel to the extent of one type and locks the wheel, as hereinafter described. Thus the armature-lever B'', at the end of both its forward and its retracted movement, revolves the type-wheel one type.

F is the type-wheel. It revolves horizontally, although it may revolve vertically or at any angle, the other devices being changed ac-

cordingly, being fastened to the lower end of the hub E'. There are no types on this wheel, as is usually the case, but instead the letters are formed on the lower ends of the little metallic posts F', (best seen in Fig. 3,) which pass through holes made in the wheel F, near its periphery, in which holes the little posts slide easily, being normally held up by the little springs F'', the free ends of which are fastened to them and the other ends to some suitable part of the wheel F, or to the hub E', or to any other suitable point. On the lower ends of these little posts, and below the type-wheel F, the types—*i. e.*, the letters, figures, or other designations used for making the desired record—are formed, and there may be more than a single letter or figure, if desired, on each post, and there may be as many of the little posts as desired, the size of the wheel F and the other parts of the apparatus being made to conform. These little posts should preferably be made of iron case-hardened, for the sake of durability and to avoid magnetization. The types receive their ink from an ink-roller, T, located in the block H, or in any other desired manner.

G G are another pair of electro-magnets placed in a second circuit, which on the passage of the current attract the armature G', which is supported on the end of a little sliding bar, G'', which passes through a block of metal, H, and projects from the front side thereof, terminating in a punch-button, H'. A spiral spring, H'', (seen in section in Fig. 3,) encircles the bar G'', one end of which takes against either the inner end of the punch-button H', or some other suitable shoulder on the bar, and the other end against a shoulder, H''', formed on the block H. This spring H'' is the retracting-spring for the armature G', and it also feeds the strip of paper when expanding.

I is a feeding-pawl. (Best seen in Fig. 3.) It is pivoted to the armature G', as seen at I', and works through a recess, I'', formed in the upper part of the block H. At its inner end it is curved upwardly, and terminates in fine sharp teeth—such as are usually used for the purpose of feeding paper or cloth in analogous devices. At its rear end a spring, I'', is fastened, the other end of which is attached

to some suitable part of the armature G'. The function of this spring is to hold the inner end of the pawl up against the paper.

K is a stop-pawl, which is located within the recess I" and in front of the feeding-pawl I. It is pivoted, as seen at K', and has a spring placed beneath it, which causes the front end, which is furnished with sharp teeth the same as the pawl I, to constantly engage with the paper and prevent it from moving backwardly. The paper S comes from a roll, as usual, which is supported on a spindle between the upper ends of the uprights L L, and passes downward over the magnets G and enters a slot, L', prepared for it between the upper surface of the block H and a thin metallic plate, L'', which is fastened upon or is let into the block H. There is a hole, L''', made in this plate, coincident with the type the impression from which is desired, through which the type strike and impress the paper, as hereinafter described. The slot is just wide and thick enough for the paper to pass easily through it, and the pawls I and K effect the feeding and holding of the paper by their pressure against it while held down by the plate L''.

M M are another pair of electro-magnets. They, when the current passes through them, attract the armature M', the lever M" of which is pivoted to the bracket M''. The free end of the armature-lever M" extends to directly above that one of the little posts F' which it is desired to depress, for the purpose of making an impression of the type on its lower end, and preferably has a little hammer-like projection, N, on its end. It is retracted by the spring N', which may be attached at its upper end to an arm, N'', and passes through a hole, N''', in the bracket M'', or in any other suitable manner. By thus placing this hammer-bearing lever over the type, instead of beneath them, and striking down upon them, instead of up against them, I avail myself of the weight of the lever and hammer in aid of the magnets which actuate them, thus securing a sharp quick blow on the type, which renders their impression more perfect, and I also make the operation of the magnets more prompt and free.

The degree of movement of the armature-lever B" is determined by the anchor D and escapement-wheel E; that of the armature-lever M" by the posts F' in one direction and by the set-screw O in the other.

The degree of movement of the armature G' and its bar G" may as well as in the other two cases be regulated in a variety of ways; but since the movement of these parts effects the feeding of the paper I prefer to regulate it by shifting the magnets G. This I do by attaching them to the slide-bar P, which can be clamped in any desired position by means of the clamping-screw P' and the block P'', attached to the clamping-screw through which the bar P passes. There may be a ring of metal or other suitable substance, P'', provided

beneath the bar P, down upon which the bar P will be clamped. By means of these devices the magnets G can be fastened in a moment at any desired distance from the armature G'. These magnets are preferably set into a hole, Q, cut in the base A, and the studs Q' Q', on which they slide while being adjusted, steady and support them, the studs resting on the top of the base A.

The operation is as follows: An intermittent current is caused to pass through the magnets B, which, acting through the armature B' and lever B" and the spring C, causes the anchor D, acting through the escapement-wheel E, to rotate the type-wheel F by intermittent or step-by-step rotation. This rotation is, however, twice as rapid as that of such wheels in ordinary instruments of this class when operated by electro-magnets, because, as already stated, the anchor acts on the escapement-wheel at both its forward and backward movement. Thus the wheel receives two forward impulses at each make and break of the current through the magnets B. A second circuit passes through the magnets G and M. The current is established through this circuit by any suitable transmitting-instrument, preferably a dial-instrument having letters, figures, and other designations, the same as those on the ends of the little posts F' in the wheel F. Whenever, therefore, this current is established, the magnets M, acting through the armature M' and its lever M", strike down the proper post, F', to make the desired impression, and at the same time the magnets G, acting through the armature G', draw back the feeding-pawl I, to take a new hold on the paper to feed it forward, the stop-pawl K meantime preventing any backward movement of the paper; and when this circuit is broken the spring H', acting through the bar G'', the armature G', and the feeding-pawl I, feeds the paper forward the desired distance, and at the same time the spring N'' retracts the armature-lever M", and the springs F" retract—i. e., lift up the little posts F'—thus restoring all these parts to their proper position for a repetition of these movements. It will thus be seen that if for any cause any one of the types on the ends of the posts F' become injured, that particular one may be replaced without disorganizing the machine, and at very slight expense; and to facilitate this I recess or cut away the upper part of the block H, as seen at R, Fig. 2, so that the spring F" of the defective type being withdrawn the post will drop down and out of the wheel F, and a new one may be in a moment pushed up into place, the spring replaced, and the machine be ready for operation again.

I do not limit myself to the details of construction shown, since many possible changes therein will be obvious to any one skilled in this art and still my invention be embodied.

Having described my invention, I claim—

1. The combination, in a printing-telegraph, of a type-wheel which is caused to revolve, and

controlled in its revolution by an escapement operated by the armature of an electro-magnet in an electrical circuit, the said type-wheel being provided at or near its periphery with 5 type adapted to move independently of the type-wheel, and provided with springs, whereby they are made to assume a definite position relative to the type-wheel when not printing, and a second circuit in which there is placed 10 an electro-magnet the armature whereof at stated times causes the type to move against the paper, substantially as and for the purposes set forth.

2. The combination, in a printing-telegraph, 15 of a type-wheel rotated by an escapement controlled by a magnet in an electric circuit, the type being loose in the wheel and capable of independent movement, and a second electric circuit in which are two electro-magnets, the 20 armature of one of which at stated times causes the type one by one to move against the paper, and the armature of the other feeds the paper, substantially as and for the purposes set forth.

3. The combination of the armature G' and 25 bar G'', provided with a punch-button and retractile spring, and the feeding-pawls I and K, and the slot L', whereby the paper may be fed through the block H prior to the operation of the machine, substantially as and for the pur- 30 poses set forth.

4. The combination, in a printing-telegraph, 35 of an electric circuit in which is placed an electro-magnet, the armature whereof, acting through a lever, rotates and locks a type-wheel, and a second circuit in which there are placed two electro-magnets, one of which, operating

through its armature and lever, feeds the paper to the instrument, and the other, operating through its armature and lever, causes the printing to be done, substantially as and for 40 the purposes set forth.

5. In a printing-telegraph, the combination 45 of an armature which when attracted by its magnets sets the feeding mechanism, a retractile spring which both retracts the armature and feeds the paper, and magnets for the attraction of the armature, provided with means whereby they may be adjusted relative to the armature, substantially as and for the purposes set forth.

6. The combination, in a printing-telegraph, 50 of the block H, the type-wheel F, the type-bearing posts F', the said block having the cut-away portion R, whereby the type may be readily removed and replaced, substantially as 55 and for the purposes set forth.

7. The combination, in a printing-telegraph, 60 of a horizontally-rotating type-wheel, paper passing below the type, and an inking device also placed below the type, so that the ink deposited upon the surface of the type will be retained thereon by gravity, and not tend to run down into the face or along the sides of the type, substantially as set forth.

Signed at New York, in the county of New 65 York and State of New York, this 18th day of April, A. D. 1884.
